UNITED STATES PATENT OFFICE.

JOHN A. DORNER AND FRED CLIFTON FRANCISCO, OF AKRON, OHIO, ASSIGNORS TO THE B. F. GOODRICH COMPANY, OF NEW YORK, N. Y., A CORPORATION OF NEW YORK.

METHOD AND MACHINE FOR MAKING CABLED STRUCTURES.

Application filed February 7, 1921. Serial No. 443,072.

To all whom it may concern:

Be it known that we, JOHN A. DORNER and FRED CLIFTON FRANCISCO, citizens of the United States, residing at Akron, in the county of Summit and State of Ohio, have invented a certain new and useful Method and Machine for Making Cabled Structures, of which the following is a specification.

This invention relates to winding a strand 10 in helical convolutions upon an article, especially a ring or endless article, and more particularly to the art of making endless machine belts such as automobile fan belts wherein the belt is formed by winding 15 a rubberized cord helically about an endless core to make a grommet. With machines used prior to our invention difficulty was had in procuring accuracy in the laying of the cord because of the irregular turning of 20 the belt upon its cross-sectional axis as it was propelled circumferentially, due in part to the tangential pull of the tensioned cord as it was wound upon the belt, and difficulty has been experienced in obtaining an accurate 25 rate control of the pitch of successive turns of the cord so as to provide a smooth, even layer of cord completely covering the core.

The general object of our invention is to provide an improved method and improved 30 apparatus for winding a strand in helical convolutions upon an article, and more particularly for interwinding a strand upon an annular article. A more specific object is to provide means for avoiding or reducing 35 the amount of turning or rolling of a flexible, annular article upon its cross-sectional axis as it is propelled circumferentially and a strand wound thereon, and for regulating or controlling that tendency, and for compensating such rolling as does occur, and thus procuring an accurate laying of successive convolutions of the strand adjacent each other to form a smooth layer of such convolutions upon the core.

45 Of the accompanying drawings:

Fig. 1 is a plan view of a belt winding machine embodying a preferred form of our invention, showing the work in place.

Fig. 2 is a front elevation of the same.

50 Fig. 3 is a side elevation of a part of the same.

Fig. 4 is a section on line 4-4 of Fig. 3.

Referring to the drawings:

10 is a frame upon which is mounted an

open sided ring winder 11 and a set of gears 55 12, 13, 14, 15, 16, 17, adapted to rotate said ring winder in either direction. 18 is a gear secured to the face of the ring winder 11, in mesh with gear 17, and formed with a radial passage 19 in continuation of the 60 radial passage 20 of the ring winder.

The ring winder 11 is journaled upon a hollow axle formed with a radial passage 65 registrable with that of the winder and is secured on said axle by a retaining plate 21. 65 Gears 12 and 13, both permanently meshed with gear 14, are loosely journaled upon a shaft 22. 23 is a belt wheel, formed on one side with a female clutch cone, loosely journaled upon said shaft, and 24 is a complementary clutch cone slidably keyed upon said shaft. 24^a is a foot-operated shifting lever for said cone clutch. 25 is a double-acting jaw-clutch slidably keyed upon said shaft 22 between gears 12 and 13, and adapted 70 to engage either gear 12 to rotate gear 14 in one direction while gear 13 runs idle or to engage gear 13 and turn gear 14 in the opposite direction while gear 12 runs idle. 25^a, Fig. 2, is a shifting lever for said jaw-clutch. 26 is a pinion secured to the end of shaft 22 and meshed with a gear 27 secured 75 to the end of a shaft 28. 29 is a grooved, work-driving roller, provided with a series of teeth or pins 30, 30, in its groove, said 80 work-driving roller being secured to the opposite end of shaft 28 and positioned in working alignment with the ring winder 11. The work-driving roller 29 is thus adapted to be driven always in the same direction, 85 clockwise as viewed in Fig. 2, when the cone clutch 24 is engaged.

Referring to Figs. 2, 3, and 4, 31, 32 are grooved work-supporting rollers loosely journaled upon the frame 10 in working 90 alignment with the work-driving roller 29 and the ring winder 11. 33, 33 is a curved series of small rollers below and in alignment with the aforementioned rollers, the end rollers of the series being grooved, and 95 all of said rollers 33, 33 being loosely journaled upon a vertically movable slide 34 mounted in a guideway 35 formed in the frame 10. 135 is a partially wound belt mounted upon said rollers in position to be 100 wound. 36 is a lever fulcrumed on the frame 10 at 37. 135^a is the belt-core and 105 135^b is a rubberized cord being wound there-

on in helical convolutions. 38 is a hand lever fulcrumed on the frame 10 at 39 and provided with a latching pawl 40 associated with a ratchet 41 formed upon the frame 10. 5 42 is a link connecting the outer end of the lever 36 with an intermediate part of the hand lever 38. The lower part of the slide 34 is formed with bearings 34^a, 34^b for a pair of beveled gears 43, 44. 45 is a hand 10 wheel adapted to turn the beveled gear 43, and 46 is a vertical screw or worm secured to the beveled gear 44. 47 is a block formed with female threads, said block being mounted upon said worm 46, and 48 is a hand 15 link connecting said block 47 with an intermediate part of lever 36. The hand lever 38 is thus adapted to raise and lower the link 42, lever 36, link 48, block 47, worm 46 and slide 34, together with the gears 43, 44 20 and the hand wheel 45, for local adjustments. With the hand lever 38 in a given position, the hand wheel 45 is adapted to raise and lower the slide 34 for either major or minor adjustments. 25 49, 49 is a short curved series of rollers loosely journaled on the slide 34 above the rollers 33 and adapted to hold belts of relatively short length, the end rollers of said series being grooved. 30 50 is a friction-braked cord spool mounted upon the ring-winder 11, 51 is a counter weight opposite thereto, and 52 is a cord-laying tube or finger mounted upon the ring winder with the axis of its cord passage lying approximately in a perpendicular radial plane with respect to said ring winder, and 35 said finger is adapted to be adjusted in said plane, its point thus being swung from or toward the work to adapt it for belts of different cross-sectional size. It is desirable 40 that the point of the cord-laying finger pass about the work in close proximity thereto. In the operation of the machine the ring winder is turned by hand until its radial 45 passage registers with that of its axle and an endless belt-core 135^a, which may be of spliced cord-cable or other suitable construction, is inserted in the ring winder and mounted upon the grooved rollers 29, 32, 50 31 and 33, as shown clearly in Fig. 2. If a belt of a new size is to be wound the slide 34 is adjusted vertically by means of the hand wheel 45 until the belt core is moderately taut when the hand lever 38 is in an intermediate position. The rubberized cord 135^b from the spool 50 is threaded through the tube or finger 52 and its end attached to the belt-core adjacent the end of said tube. The core is then tightened by lowering the hand lever 38, the jaw-clutch 35 is caused to engage the gear 12, and power is applied 55 through the cone clutch 24, simultaneously starting the circumferential rotation of the core, clock-wise as viewed in Fig. 2, and rotation of the ring winder 11, counter-clock-

wise as viewed in Fig. 3, thus winding the cord helically about the core.

If a belt of a new size is to be wound, it may be necessary to make several trials with the hand lever 38 in different positions in order to cause the first course of the helical winding to return accurately to its starting point, but when, by such trials, it has been determined what position of the hand lever 38 is necessary to produce this result, additional belts of the same size may be started with said lever secured in the particular notch of the ratchet 41 which has been found proper for that size of belt. We find that in this way it is quite practicable to secure an accurate return of said first course of cord upon succeeding belts of the same size. In practice it is usually found that the ratchet 41 provides sufficiently small adjustments to secure the desired accuracy of return of the first course of cord, but obviously more minute adjustments for that purpose may be had by turning the hand wheel 45. The first course being laid, the winding is continued, each course being laid adjacent the last laid course until the core is completely covered with a layer of cord. 85

The small rollers 33, notwithstanding the tangential pull of the tensioned cord from the spool 50, by reason of their large aggregate surface of contact with the work, reduce the tendency of the core, or partly wound belt, to twist or roll upon its cross-sectional axis as it is rotated circumferentially, and especially prevent irregularity in such rolling. 100

If successive convolutions of the cord tend to climb upon each other the tension upon the core is lessened by raising the hand lever 38, and if they tend to spread apart, said hand lever is lowered, tightening the core or partly wound belt. The work-driving roller 29 being rotated at a constant speed relative to the speed of the ring winder and being provided with the teeth 30 to prevent slippage of the work thereon, an immediate temporary effect of tightening the belt core is, by stretching the part of the core passing between the ring winder 11 and the work driving roller 29, to retard the passage of the belt past the ring winder, and thus cause the convolution being laid to lie closer behind or more firmly against the last laid convolution. This effect is small as well as temporary, however, when, as shown, the work-driving roller is positioned closely posterior to the ring winder, the intervening part of the belt being too short to afford much elongation and consequent retarding of the part of the belt passing the ring winder. 115

A continuing effect contributing to the same purpose results from stretching the belt in that the convolutions, of which there are of course a fixed number in the length of 120

the belt, are drawn to a steeper pitch by the lengthening of the belt, said steeper pitch calling for a slower relative speed of the ring winder, but as the relative speeds of the ring winder 11 and work driving roller 29 are constant, the cord continues to be laid at the same angle to the belt's axis after the previously laid convolutions have had their pitch increased by the stretching of the belt. The 10 new convolution is thus caused to converge to the convolution previously laid. Both the temporary and continuing effects referred to obviously are reversed by slackening the belt, causing the new convolution to lie less tightly 15 against the convolution last laid and thus avoid climbing of the cord. A skilled operator by careful handling of the hand lever 38 can lay the cord with a high degree of 20 accuracy and even pressure between convolutions.

An advantage of the construction shown and described is that, the work being pulled through the winder by the core-driving roller 29, and the tensioning means being on 25 the delivery side of said roller and on the receiving side of the winder, the "temporary" effect and the "continuing" effect described above are cumulative, so that the operator obtains a very prompt response and, however 30 abruptly he moves the hand lever 38, there is but a single change in the course of the thread upon the work, whereas if the structure were such that an increase of tension 35 would speed up the portion of the core passing through the winder, instead of retarding it, said "temporary" effect would be opposed to said "continuing" effect and might completely nullify it for a time when the 40 tension was changed, which would make the accurate laying of the cords more difficult if not impossible.

When the layer of cord is completed the machine is stopped, the cord severed and the last end thereof is attached to the belt. The 45 operation may then be repeated upon the same belt with the ring winder turning in the opposite direction, the jaw-clutch 26 being shifted to engage the gear 13, to place another layer of cord upon the belt with its 50 convolutions lying approximately at right-angles to those of the first layer.

Modifications may be resorted to without departing from the scope of our invention and we do not wholly limit our claims to the 55 specific construction shown.

We claim:

1. A winding machine comprising a ring winder, means including a drive roller adapted to propel an endless core in a 60 straightened path through said ring winder, and tensioning means for said core comprising a plurality of rollers mounted upon a common support and means for moving said support toward and from the aforementioned drive roller.

2. A winding machine comprising a ring winder, means including a drive roller adapted to propel an endless core in a straightened course through said ring winder, a tension roller for said core, a slidible 70 mounting for said tension roller, means for making major adjustments of said slidible mounting toward and from the said drive roller to adapt the machine for different sized articles, and a lever adapted to move 75 said slidible mounting to vary the tension of the article while it is being wound.

3. A winding machine comprising a ring winder, a plurality of rollers adapted to cause an endless core to follow a straight- 80 ened path through said ring winder, a tension roller for said core, and a hand lever connected with said tension roller and adapted to be operated to vary the tension of said core at will during its passage 85 through said ring winder.

4. A winding machine comprising a ring winder, a plurality of rollers adapted to cause an endless core to follow a straight- 90 ened path through said ring winder, a tension roller for said core, a hand lever operatively connected with said tension roller, and adapted to be operated to vary the tension of said core at will during its passage 95 through said ring winder and means for securing said operating lever in different positions.

5. A winding machine comprising a ring winder, means for driving an endless core through said winder, a tension roller for said core, a lever for moving said tension roller to vary the tension of said core, and adjustable connecting means between said lever and said roller, said means being adapted to be lengthened or shortened to adapt the machine for cores of different circumferential 105 length.

6. A winding machine comprising a ring winder, means for driving an endless core through said winder, a multiplicity of 110 closely spaced tensioning rollers arranged in curved formation and adapted to prevent said core from turning upon its cross-sectional axis as it is so driven, and means minutely and instantly responsive to the 115 operator's manipulation for varying the tension of said core while it is so driven.

7. A winding machine comprising a ring winder, means for driving the same, means for supporting and propelling an endless 120 flexible core through said ring winder, a multiplicity of tensioning rollers arranged in curved formation, a common mounting for said tensioning rollers, and means for adjusting said mounting from and toward 125 said ring winder during the winding operation.

8. A winding machine comprising a ring winder, means for driving the same, means for supporting and propelling an endless, 130

flexible core through said ring winder, a multiplicity of tensioning rollers arranged in a curved series, and a similar series of tensioning rollers positioned between the 5 first mentioned series and said ring winder.

9. A winding machine comprising a ring winder, means for driving the same, means for supporting and propelling an endless flexible core through said ring winder, a 10 multiplicity of tensioning rollers arranged in a curved series, a similar series of tensioning rollers positioned between the first-mentioned series and said ring winder, a common mounting for the rollers of both 15 said series, and means for adjusting said mounting from and toward said ring winder during the winding operation.

10. A winding machine comprising a ring winder, a plurality of rollers adapted 20 to cause an endless core to follow a straightened path through said ring winder, a plurality of tensioning means adapted for cores of different sizes, said plurality of tensioning means being mounted upon a common 25 support, and means for moving said support toward and from the aforementioned rollers.

11. A winding machine comprising a 20 winder, means at a fixed distance from said winder for pulling a core through said 30 winder, means for reversing said winder

with relation to the core-pulling means, and means positioned, in effect, on the opposite side of the winder from the core pulling means, for varying the tension of the part of the core passing to the winder. 35

12. The method of making a cabled structure which comprises feeding a core past a point, winding a strand thereon at said point, and varying the tension of said core during the winding to control the 40 positioning of the strand thereon.

13. The method of making a grommet which comprises feeding an annular core past a point, winding a strand thereon at said point, and varying the tension of said 45 core to control the positioning of the strand thereon.

14. The method of making a cabled structure which comprises feeding a core past a point and winding a strand thereon adjacent said point, the relative speeds of said feeding and winding being in fixed ratio, and stretching and relaxing said core during the winding of the strand thereon to control the 50 positioning of the latter. 5

In witness whereof we have hereunto set our hands this 27th day of January, 1921.

JOHN A. DORNER.
FRED CLIFTON FRANCISCO.
